GARMENT PRESSER

Meyers Martin Berger, Youngstown, Ohio

Application April 15, 1949, Serial No. 87,587

4 Claims. (Cl. 223—57)

1

This invention relates to garment presses and more particularly to a garment presser for preparing the body portion of a suit of coveralls or overalls.

The principal object of the invention is the provision of a garment presser for preparing the body portion of overalls or coveralls.

A further object of the invention is the provision of a garment presser which may be easily operated to automatically position, press and deliver a garment.

A still further object of the invention is the provision of a garment presser incorporating means for automatically adjusting the pressing elements to the size of the garment being pressed.

A still further object of the invention is the provision of a simple and efficient garment presser which may be inexpensively constructed and which is capable of repeated operation with a minimum of attention.

The garment presser shown and described herein has been designed particularly for pressing the body portion of coveralls, overalls, work jackets and the like such as commonly handled by commercial laundries in connection with laundering and pressing various workman's attire. The practice heretofore in such laundries has been to press the arms and legs of the coveralls or overalls on special devices insertable in the arms and legs and expandable to press the same uniformly. The body portions of the garments have then been pressed by hand operations on conventional pressing machines usually of the flat bed type. This necessitates a number of operations per garment in pressing the same which increases the processing time of the garment as well as the cost thereof.

The present invention relates to a device which will receive the body portion of the garment to be pressed; for example, a coverall, overall or uniform jacket, which will then move the same into position between a pair of pressing members at least one of which is movably mounted and which then move into engagement with the garment and press the same. The form on which the garment is positioned is relatively elastic and/or expandable in controlled degree so that the same automatically fills out the garment being pressed regardless of its size. The garment is then easily finished by subjecting the same to the arm and leg pressing operation which eliminates all hand work on the garment and enables the same to be processed rapidly and economically.

With the foregoing and other objects in view

2

which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

10 The invention is illustrated in the accompanying drawing, wherein—

Figure 1 is a front view of the garment presser.

Figure 2 is a side view of the garment presser with parts broken away.

15 Figure 3 is a vertical section taken on line 3—3 of Figure 2.

By referring to the drawings and Figures 1 and 2 in particular it will be seen that the garment presser comprises a vertical framework 10 having a pair of pressing plates 11 and 12 positioned vertically therein and at the sides thereof and spaced with respect to one another. The pressing plate 12 is mounted for horizontal movement as by a plurality of tubular guides 13—13 and an energized hydraulic piston and cylinder assembly 14. The pressing plate 12 is provided with a plurality of horizontally extending arms 15—15 which register with the tubular guides 13 and thereby support the pressing plate 12 and a piston rod 16 of the piston and cylinder assembly 14 is connected to the pressing plate 12 so that the same may be moved thereby.

The pressing plate 11 is illustrated as being fixed to the framework 10 in spaced relation to the movable pressing plate 12 but may obviously be formed as a movable member by duplicating the mechanism supporting and moving the movable presser plate 12, if desired.

An expandible form 17 is loosely suspended from 40 a traveler 18 which in turn is provided with rollers 19 engaging tracks 20 in a beam 21 pivotally mounted in the uppermost portion of the framework 10 and between the spaced side portions thereof, as best shown in Figure 1 of the drawings, the beam 21 being pivotally mounted by a transverse pivot 22 and having a rearwardly extending portion 23 which is provided with a counterweight 24. A stop member 25 is positioned near the foremost end of the beam 21 so that the traveler 18 is limited in its travel on the beam 21 between the stop 25 and the pivot 22.

By referring to Figure 2 of the drawings it will be seen that when the traveler carrying the expandible form 17 is in position adjacent the 55 pivot pin 22, the expandible form 17 is disposed

between the pressing plates 11 and 12. When the traveler is adjacent the stop member 25, the expandible form 17 is in position in front of the machine and substantially away therefrom so that a garment may be readily positioned thereon or removed therefrom.

Still referring to Figure 2 of the drawings it will be observed that a control for the beam 21 is disclosed and comprises a flexible cable 26 which is extended to a desirable location and provided with a pedal 27 whereby the operator of the device may tilt the beam 21 upwardly or downwardly so that the traveler 18 will move into or out of the area of the pressing plates 11 and 12. It will be observed that the expandible form 17 is loosely pivoted to the traveler 18 as by longitudinal and transverse pivots 28 so that the tilting of the beam 21 will not tilt the expandible form 17.

By referring to Figure 3 of the drawings a vertical section of the expandible form 17 may be seen and it comprises a rubber-like envelope 29 having a plurality of flexible cross pieces 30 therein and limiting the thickness of the expandible form 17 to that desired. The flexible cross pieces 30 are also secured to a vertical support 31 which extends vertically through the device and which is pivoted to the traveler 18. The expandible form 17 is thereby rendered capable of expanding sidewardly, as shown in Figure 1 of the drawings, so as to increase its effective width but it is rendered incapable of expanding to increase its effective thickness. The form is preferably inflated and for this purpose a valve stem 32 is provided and the form may alternately comprise an envelope enclosing a distortable and/or expandible material such as foam rubber or the like so that pressing action of the pressing plates 11 and 12 thereagainst will result in increasing the width of the expandible form 17 but not the thickness.

Thus, a small garment positioned on the form 17 and secured thereto as by buttoning or fastening the same in the usual manner is pressed as the form 17 expands therein and the pressing plates 11 and 12 engage the front and back surfaces thereof. A larger garment merely requires the additional expansion of the form 17 which occurs when the pressing plates 11 and 12 engage thereagainst. The pressing plates 11 and 12 are heated as by introducing steam thereinto and the expandible form 17 may also be heated by the same means or an equivalent structure.

Means for moving the movable pressing plate 12 is provided and comprises a hydraulic pump 33 driven by an electric motor 34 and connected by piping 35 and 36 with the piston and cylinder assembly 14 by way of a four-way control valve 37 and a reservoir 38.

It will thus be seen that a simple and efficient garment presser has been disclosed which may be advantageously used in the pressing of the

body portions of garments such as coveralls, overalls, uniform jackets and the like which meets the several objects of the invention.

Having thus described my invention, what I claim is:

1. A garment presser comprising a framework having a tilttable beam positioned in the upper portion thereof and extending outwardly therefrom, and an expandible form loosely suspended therefrom and movable therealong as by tilting the said beam, a pair of spaced presser plates in said framework and engageable with the said form when the same is moved therebetween whereby a garment on the form may be pressed.

2. A garment presser comprising a vertical framework having a horizontally disposed beam mounted by a pivot pin in the upper portion thereof and extending outwardly therefrom, the said beam being movable in a vertical arc based on said pivot pin and an expandible form suspended therefrom and movable therealong as by tilting said beam, a pair of vertically disposed spaced presser plates in said framework and engageable with the said form when the same is moved therebetween, and means for moving at least one of the said pressing plates toward the other whereby a garment on the form may be pressed.

3. A garment presser comprising a vertical framework having a horizontally disposed beam movably mounted in the upper portion of said framework by a pivot pin located inwardly from the ends of said beam, the said beam extending outwardly therefrom and movable on a vertical arc based on said pivot pin, and an expandible form suspended from said beam on one side of said pivot pin and movable therealong, a pair of vertically disposed spaced presser plates in said framework and engageable with the said form when the same is moved therebetween, and means for moving at least one of the said pressing plates toward the other whereby a garment on the form may be pressed, and means for tilting the said beam to cause the said form to move into and out of the said framework.

4. The structure defined in claim 3 including a counter weight on the end of the beam opposite from the said expandible form and wherein the means for tilting the beam comprises a lever and cable connected therewith.

MEYERS MARTIN BERGER.
